(No Model.)

A. M. JOHNSON.

WATCHMAN'S TIME RECORDER.

No. 287,291.

Patented Oct. 23, 1883.

UNITED STATES PATENT OFFICE.

ALBERT M. JOHNSON, OF NEW HAVEN, CONNECTICUT.

WATCHMAN'S TIME-RECORDER.

SPECIFICATION forming part of Letters Patent No. 287,291, dated October 23, 1883.

Application filed June 11, 1883. (No model.)

To all whom it may concern:

Be it known that I, ALBERT M. JOHNSON, of New Haven, in the county of New Haven and State of Connecticut, have invented a new 5 Improvement in Watchmen's Clocks; and I do hereby declare the following, when taken in connection with accompanying drawings and the letters of reference marked thereon, to be a full, clear, and exact description of the 10 same, and which said drawings constitute part of this specification, and represent, in—

Figure 1, a front view; Fig. 2, a side view; Fig. 3, a detached view, showing the connection between the time-movement and the slide 15 which carries the marker; Fig. 4, a front view; and Fig. 5, a sectional view, showing the train which operates the registering-pointers.

This invention relates to an improvement in that class of clocks which are located at a 20 central point in a territory to be watched, and with which several stations at different points in said territory communicate, and so that the watchman at one station may make a communication to the central point, which will automatically record his presence at said station 25 at such predetermined time, commonly called "watchmen's clocks," from the fact that the central station is in connection with a time-movement, whereby the precise time 30 at which the watchman was at such station will be indicated. The clock now more generally used for this purpose is one in which a revolving disk is arranged in connection with the time-movement, so as to make one revolution every twelve hours, and upon this disk 35 a marker is brought to bear from the several stations at predetermined times, and so that the watchman's presence at such stations will be indicated on the disk, or his absence from 40 the station noted by the absence of a corresponding mark upon the disk. These disks are required to be renewed daily, and so that to compare several days with each other it is necessary to examine several independent 45 disks.

The principal object of my invention is to construct an apparatus by which a single disk may be employed for a number of days—say one week; and the invention consists in the 50 combination of mechanism, as hereinafter de-

scribed, and more particularly recited in the claims.

A represents the main shaft. On this shaft is the drum B, upon which the cord or weight which drives the movement is wound, or it 55 may be a spring-barrel attached thereto. The shaft is provided with the usual pawl and ratchet between it and the main wheel C, whereby the clock-movement may be wound. From this main wheel a suitable train of gearing 60 communicates to the pointers, here represented as through a vertical shaft, D, communicating with the train by bevel-pinions E, the time-pointers being above at any suitable distance, and the usual time-wheels taking 65 their rotation from the pinion on the vertical shaft D. (Not shown.) The main shaft is arranged to make one revolution each twelve hours. Onto the main shaft a circular plate, 70 F, is fixed, and upon this the indicator-disk H is placed. This disk is preferably of paper, and the plate F of wood or other semi-soft material. The disk is secured to the plate F by a collar, I, over the center shaft, and a nut or pin to bear upon the collar, so that the 75 disk will revolve with the plate F one revolution in twelve hours, and may be easily adjusted circumferentially around the center shaft by loosening the fastening which secures it to the plate. The disk H is divided radi- 80 ally into twelve parts, corresponding to the twelve hours, and circumferentially divided, say, into seven parts, representing the seven days of the week. At some convenient point, preferably in a central line below the main 85 shaft, the indicator is arranged. The indicator consists of a lever, K, carrying a sharp point, a. This lever is hung upon a pivot, b, and so that the point will stand in front of the disk, as shown, and is provided with a light 90 spring, L, sufficient to support the lever in a position holding the point away from the surface of the disk H.

M is a magnet arranged in an electrical circuit. The lever K is provided with a corresponding armature, N, and so that when the circuit is closed the armature attracted to the magnet will bring the point a onto the face of the disk H and make an indentation or perforation thereon, and when the circuit is broken 100

the pointer will be withdrawn out of contact with the disk. Several stations are arranged in the same circuit with the magnet M, and when a watchman at one station closes the circuit that closing will be indicated upon the disk H, and the time at which such closing was made will be also indicated, for the reason that the disk H is set corresponding to the hours of time; hence if the circuit be closed 5 in the position seen in Fig. 1, the disk will not only indicate that the circuit was so closed, but will also indicate that the circuit was closed at six o'clock. The disk continues its rotation as the time passes, and at the next 10 point where the watchman closes the circuit another indentation will be made—say at some point between six and seven—which will indicate the time when the circuit was closed at that point, and so on, passing around the disk 15 the twelve hours will indicate the number of times the circuit has been closed by the watchman. The several indications thus produced upon the disk will all be in the same circumferential line during the first twelve hours— 20 say beginning at six at night until six in the morning. Now, were there no provision for a change of relative position of the pointer to the disk, it would be necessary to remove the disk and introduce a new or fresh one. To 25 avoid this I arrange the lever K and its operating mechanism upon a slide, P, between vertical guides R R, and so that the slide with the lever may be moved freely up and down. Connected with this slide is a vertical toothed 30 rack, S, into which a pinion, T, on a shaft, U, works. On this shaft U is a toothed wheel, V, the teeth of which stand in the path of a stud, d, on a wheel, e, which is in connection 35 with the time-train, and which wheel may 40 make one revolution each twelve hours, and in such revolution the stud d will engage one of the teeth on the toothed wheel V, and turn that wheel and shaft one point, which turning will be communicated to the rack S 45 and raise that with the lever it carries one point. This movement will be caught by the pawl f engaging the toothed wheel V, as seen in Fig. 3. This movement will bring the point a to a position above the circumferential line 50 in which it stood in the last revolution of the disk, and so that the point a, brought into contact with the disk, will make an impression within the last circle and continue on that inner circle during the next twelve hours, and 55 at the expiration of this second twelve hours the stud d on the wheel e will again turn the ratchet V one point, and raise the point a to a position nearer the center and into a circumferential line with the second line, and so continue. The first line of impressions, say, is beginning 60 six o'clock Sunday night, and on the line marked S. After twenty-four hours the second line above (marked M) will be reached, beginning Monday night at six o'clock. The intermediate twelve hours—that is, beginning 65 six o'clock Monday morning, if the record is to be made—will be on a line intermediate be-

tween the two lines S M, and so continue through the week, the point a rising step by step to make the record for successive days 70 upon different circumferential lines corresponding to the respective days, and this change is automatically made, avoids the frequent change of disk, and preserves on one disk the record for a whole week or longer 75 time, if desirable, according to the extent of radial feed imparted to the point a or size of the disk.

I have represented the impulse to produce the action of the point a as through an electrical circuit; but this may be done by other known means for communicating an impulse or movement of the pointer for like purposes. By arranging the disk on the main shaft of the time-movement, the disk itself may serve to 80 indicate the time without necessarily employing the vertical shaft D and the communication therefrom to the pointers above. The position of the disk with relation to the lever K, or a pointer, h, thereon, as seen in Fig. 1, will 85 indicate the time on the disk.

I have represented and described my clock as arranged for an open circuit; but it will be readily understood that it may be on a closed circuit, if desirable, by simply making the 90 changes usual for converting a closed to an open circuit.

The arrangement of the disk directly upon the main or twelve-hour shaft of the time-movement may be employed in connection 95 with other recording mechanism. I therefore do not wish to be understood as limiting this arrangement of the disk to my particular recording devices.

In case the record of the watchman is to be 105 made only during, say, from six at night to six in the morning, the movement of the slide carrying the point a need be made only once in twenty-four hours. In that case the gear which carries the stud d may revolve only once 110 in twenty-four hours, and such is the representation in Fig. 2; but if the record is required to be made during each twelve hours, then that wheel would be required to make one revolution in each twelve hours, or a corresponding stud, d, on the opposite side of the wheel. Instead of working the slide upward, 115 it may work downward by reversing the rack.

As a means for communicating the presence of the watchman at a certain point, as well as 120 to record the fact that he has been to that precise point at such predetermined time, I employ a circuit-breaker, with an indicator in connection with it, as seen in Figs. 4 and 5. This consists of a driving-shaft, i, to which is 125 applied a main driving-spring, l, to which shaft a key is applied by the watchman, who turns it to move the finger m from its stop n to another stop, r, as seen in broken lines, Fig. 4, from which stop r the finger m will be forced 130 to return under the action of the main spring to its stop n when the power which turned it is removed.

On the main shaft i is a gear, t, which works

into a pinion on the shaft *u*, which carries a wheel, *w*, and on this wheel is a projection, 5, said wheel and projection forming a cam. In the path of this cam 5 stands a metal point or finger, 6, from which a line, 7, runs to one pole of the magnet. From the other pole a line, 8, returns into connection with one of the plates, the metal point 6 being insulated from that plate. Now, after the finger *m* has 5 been turned, as before described, to the stop *r*, the mainspring will act to return that finger, and at the same time will cause the wheel *w* to revolve and bring the cam 5 on the wheel into contact with the metal point 6, as seen in 15 broken lines, and thereby close the circuit, the cam 5 passing on and immediately breaking the circuit, the time which the circuit is closed being sufficient to produce the record on the disk.

20 From the shaft of the cam a train of gearing—say of four wheels—communicates power to four corresponding shafts, each of which carries a pointer on a dial-plate, 9, the first indicating units, the second hundreds, the 25 third thousands, and the fourth ten thousands, as in the usual registering devices. The first rotation of the cam will carry the unit-pointer one point, and each of the others a corresponding portion of one point; hence the number of 30 times that the circuit is broken will be shown by the pointers on their respective dials. A person in charge having the record of these dials may any time upon inspection ascertain how many times the circuit has been closed or 35 broken, as the case may be.

The several stations at which at predetermined times the watchman is to be present are provided with such an indicator. Each indicator will record the number of times which 40 the watchman was present at that point, and the clock itself will record the total number of times the circuit has been closed or broken, as the case may be, and the time at which such closing or breaking was performed. While 45 this circuit-breaker and its registering apparatus are particularly adapted to my improved clock, it will be apparent that they may be used in connection with other watchmen's clocks and make a corresponding record. I therefore

do not wish to limit this part of my invention 50 to my particular construction of clock; nor do I wish to be understood as broadly claiming the mechanism described by which the circuit is closed and broken, as this I am aware is not new, the gist of this part of my invention being in combining with such a circuit-closer a registering mechanism which will indicate the 55 number of times the circuit has been closed.

To indicate upon the recording-disk the registration from a particular station, the watchman may be required to make, say, one operation of the circuit-closer at one station, two at the next, three at the next, and so on, which would cause the point or marker on the disk to make one, two, three, and so on marks or 60 65 depressions; or the cam may have one projection for one station, two for the next, and so on, the cam closing and breaking the circuit one, two, or three times accordingly.

I claim—

1. The combination of the disk *H*, arranged 70 upon the twelve-hour shaft of the time-movement, the vertical slide *P*, carrying the marker-lever *K*, the toothed wheel *V* in connection with said slide, and the wheel *e* in connection with the time-movement, and carrying a stud, *d*, whereby at predetermined times a radial movement is imparted to said slide and marker, substantially as and for the purpose described.

2. In combination with a watchman's clock, 80 substantially such as described, a circuit-closer consisting of the main driving-shaft *i*, the spring applied thereto and fitted to engage with the watchman's key, the finger *m*, stops *n r*, cam 5 in gear-connection with the main shaft, the 85 metal-pointed finger 6, standing in the path of said cam 5, and in connection with one line from the clock, the other line in connection with the frame of the circuit-closer, and a series of shafts carrying pointers, the said shafts 90 in gear-connection with the main shaft, and whereby each movement of the finger *m* produced by the watchman will be indicated by the said pointers, substantially as described.

ALBERT M. JOHNSON.
